(57) CLAIM

The ornamental design for a decorative convertible wrist purse, as shown.

DESCRIPTION

FIG. 1 is a top view of a decorative convertible wrist purse showing my new design;

FIG. 2 is a bottom view thereof;

FIG. 3 is a side view thereof; and,

FIG. 4 is a perspective view thereof where the broken line showing of environment in the drawing is for illustrative purposes only and forms no part of the claimed design.
